UNITED STATES PATENT OFFICE.

EDWIN A. BOARDMAN, OF TONO, WASHINGTON.

BABY-PEN.

1,009,378.

Specification of Letters Patent. Patented Nov. 21, 1911.

Application filed March 27, 1911. Serial No. 617,113.

To all whom it may concern:

Be it known that I, EDWIN A. BOARDMAN, a citizen of the United States, residing at Tono, in the county of Thurston, State of Washington, have invented certain new and useful Improvements in Baby-Pens; and I do hereby declare the following to be a full, clear, and exact description of the invention, such as will enable others skilled in the art to which it appertains to make and use the same.

This invention relates to baby pens, more particularly to those designed to be compactly folded for storing.

The primary object of this invention is to provide a light and strong pen composed of slatted sections hingedly connected together end to end, one of the terminal sections being provided with novel spring controlled hooks which automatically lockingly engage over a vertical rod passing through the ends of the slats of the other terminal section simultaneously with the manual moving into interdigitating position of both end sections.

A second object of the invention is to provide a pen composed of sections which may be folded together, or may be disposed in any desired angular position relatively to each other with minimum exertion, the sections further being equipped with novel means for positively preventing the upper ends of the vertical rods which hingedly connect the sections from at any time projecting above the top faces of the uppermost slats of the sections so that injury to the pained infant is positively prevented as is also laceration of the hands and clothes of the attendant.

With the above objects in view the invention consists in certain novel details of construction and combination of parts hereinafter fully described and claimed, it being understood that various modifications may be made in the minor details of construction within the scope of the appended claims.

In the accompanying drawing forming part of this specification:—Figure 1 is a plan view of a baby pen embodying my improvements. Fig. 2 is a side elevation of the pen. Fig. 3 is a side elevation of the pen in folded position. Fig. 4 is a fragmentary perspective view illustrating a leaf spring for preventing the upper end of the related vertical pivot rod from projecting above the top face of the uppermost slat

of one of the pen sections. Fig. 5 is a cross sectional view taken on the line 5—5 Fig. 2. Fig. 6 is a cross sectional view taken on the line 6—6 Fig. 2.

Referring now to the drawing in which like characters of reference designate similar parts, 10 designates in general a pen formed of a plurality of hingedly connected sections 11 each of which is composed of a plurality of spaced slats 12, the confronting ends of the slats of meeting sections being interdigitated, and a vertically disposed rod 13 passed through and pivotally connecting together interdigitating slats of adjacent sections. Fitted on each pivot rod between the interdigitating ends of adjacent section slats are washers 14, the washers being arranged in pairs as shown in Fig. 4 in order to promote the free pivotal movement of the sections when setting up or folding the pen. The ends of the slats of each terminal section are held in spaced relation to one another by metallic vertically arranged transverse strips 15. The ends of the slats of one terminal section are further connected together by a vertically disposed rod 16 similar to the pivot rods 13 above described, and provided with rivet heads at its opposite ends which prevent withdrawal of other terminal section are formed with longitudinal slots 17 which receive the rod 16 when the bars of both terminal sections are manually interdigitated.

For manually moving the free ends of the terminal sections into interlocking engagement when it is desired to erect the pen for use the following construction is employed: Arranged on the slotted end of one of the terminal section slats 12 is a forked plate 18 the branches 19 of which extend longitudinally along opposite sides of the slot in the slat and project considerably beyond the extreme end of the slat, the extremities of the branches being rounded as shown at 20 and forming guide surfaces for directing the rod 16 of the mating terminal section into the slot as clearly shown in Fig. 6. A catch 21 is pivoted at its intermediate portion to the plate and is provided with a hook-shaped bill 22 the extreme outer edge 23 of which is inclined transversely and inwardly across the slot in the bar and forms a bearing surface against which the rod 16 bears during its passage into the slot and forces outwardly the catch against the pressure of a leaf spring 24 the catch returning

to its initial position upon the rod reaching final position and locking the rod in its final position as shown in Fig. 6. Two or more of these catches may be employed but it is preferable to use two of the catches in order that unlocking of the terminal sections may be accomplished in a minimum time when it is desired to collapse or fold the sections for storing.

10. It will be noted that the ends of each pivot rod 13 are equipped with rivet heads, and in order to prevent the rivet heads on the upper ends of the rods from projecting above the top slats of the sections when the pen is set up, a leaf spring 25 is secured at one end in any preferred manner to the under face of each alternate top slat, this leaf spring bearing against the underlying end of the top slat of the next adjacent section as shown in Fig. 4 and being provided with an orifice 26 through which the pivot rod, which connects the sections, extends. This spring exerts a spreading pressure against the confronting faces of both of said top slats and serves to maintain the uppermost top rail in snug engagement with the rivet head of the pivot pin regardless of how much play exists between the interdigitating ends of the sections due to mutual wear upon the parts. In this manner injury to the penned infant or tearing of the hands or clothing of an attendant when setting up or collapsing the pen is positively prevented.

What is claimed, is:—

35. 1. A pen comprising a series of sections placed end to end and pivotally connected together, each of said sections comprising a plurality of approximately parallel slats,

the opposing ends of adjacent sections interdigitating, pivot pins passed through said interdigitating ends and provided at their opposite ends with heads, and a tension device secured to the under face of the top rail of one section and bearing against the uppermost face of the interdigitating end of the next adjacent section, said tension device exerting spreading pressure against the confronting faces of said slats, and maintaining said uppermost slat in constant abutting contact with the uppermost retaining head of the related pivot rod.

2. A pen including sections placed end to end and pivotally connected together, the terminal sections comprising longitudinal spaced slats the free ends of the slats of each terminal section being held in fixed spaced relation, the slats of one of said terminal sections being longitudinally grooved, a rod disposed transversely across and connecting the slats of the mating terminal section and adapted to enter said slots, a forked guide plate on the free end of one of said slotted slats having its branches projecting beyond the extreme end of the slat and equipped with rounded extremities, said rounded extremities forming guides surfaces for directing said rod into said slots, and a spring controlled catch on one of said slotted slats automatically engaging with said rod upon advance of said rod into said slots.

In testimony whereof, I affix my signature, in presence of two witnesses.

EDWIN A. BOARDMAN.
